UNITED STATES PATENT OFFICE.

CHARLES B. SCHOENMAN, OF WILKINSBURG, AND RALPH M. HOUCK, OF SWISSVALE,
PENNSYLVANIA.

JOINT FOR ELECTRICAL CONDUCTORS.

1,225,366.

Specification of Letters Patent. Patented May 8, 1917.

Application filed September 11, 1916. Serial No. 119,384.

To all whom it may concern:

Be it known that we, CHARLES B. SCHOENMAN and RALPH M. HOUCK, citizens of the United States of America, residing at Wilkinsburg and Swissvale, respectively, county of Allegheny, and State of Pennsylvania, have invented certain new and useful Improvements in Joints for Electrical Conductors, of which the following is a specification.

This invention relates to joints for electrical conductors and has for its object to provide means in a manner as hereinafter set forth, whereby two or more conductors can be joined or spliced with each other.

A further object of the invention is to provide a joint for the purpose set forth having means to facilitate the joining or splicing operation when setting up a joint between two or more electrical conductors.

A further object of the invention is to provide a joint for electrical conductors which is simple in its construction, strong, durable, efficient, conveniently made, neat, labor saving, and comparatively inexpensive with respect to the joints now in general use.

With the foregoing and other objects in view the invention consists of the novel construction, combination and arrangement of parts as hereinafter more specifically described and illustrated in the accompanying drawing, wherein is shown an embodiment of the invention, but it is to be understood that changes, variations and modifications can be resorted to which come within the scope of the claims hereunto appended.

In the drawings wherein like reference characters denote corresponding parts throughout the several views:

Figure 1 is a plan view illustrating a four-way or cross joint, in accordance with this invention; showing the adaptation thereof in connection with four electrical conductors, the insulation of two of the latter being shown in section.

Fig. 2 is a plan and Fig. 3 an edge view of one of the sections of the four-way or cross joint, in accordance with this invention.

Fig. 4 is a plan of the two sections of a three-way or T-joint, in accordance with this invention and Fig. 5 is an edge view of one of said sections.

Fig. 6 is a plan of the two sections of an

L-joint, in accordance with this invention and Fig. 7 an edge view of one of said sections.

Fig. 8 is a plan of the two sections of a straight joint in accordance with this invention and further showing one end of said sections, not abutting, a pair of conductors which are to be joined, the insulation being partly cut away from each of the conductors.

Fig. 9 is a plan of a pair of sections of a V-joint in accordance with this invention.

A joint for two or more electrical conductors, in accordance with this invention, consists of a pair of weldable sections or elements of a contour corresponding to the direction or directions in which the conductors which are to be joined or spliced extend. Referring to Figs. 1, 2 and 3 of the drawing, which shows a four-way or cross joint, 1 denotes one section of the joint and 2 the other section. Each of these sections consists of an alloy solder now in general use by the electrical trade and each of said sections has four arms, as indicated at 4, 5, 6 and 7, and each of said arms is formed with a groove 8 for the reception of one end of a conductor 9, the said end having the insulation removed therefrom. One arm of the section 1 has a lug 10 of the same material from which the section is made and said lug 10 is disposed laterally with respect to said arm. One arm of the section 2 has a lug 11 of the same material from which its respective section is made and furthermore extends laterally with respect to said arm. The lugs 10 and 11 are oppositely disposed with respect to each other when the sections are mounted to form the joint. The lugs 10 and 11 are of less thickness than either of the arms of either of said sections. Each of the arms of said sections is semi-cylindrical in cross section and has the free end thereof slightly reduced, as at 12.

When the sections of the four-way or cross joint are used for the purpose of joining or splicing four electrical conductors, see Fig. 1, the insulation is partly removed from the conductors 9 and the ends of said conductors 9 which are cleared of insulation are seated in the grooves 8 of the arms 4, 5, 6 and 7 of the section 2. The section 1 is then mounted upon the section 2, but prior to the mounting of the said sections 1 and 2 relatively to each other, the inner faces of said sections are provided with soldering 110

paste or flux, the two sections are then brought together and are connected together by the lugs 10 and 11. The lug 10 is bent around one of the arms of the section 2 and the lug 11 bent around one of the arms of the section 1, as indicated in full and dotted lines in Fig. 1. The lugs in such position retain the sections of the joint connected with the conductors.

10 After the sections are in place, a soldering tool, having the jaws thereof corresponding in contour to the shape of the joint, is heated to a proper temperature, and then placed over the sections 1 and 2, the tool is operated 15 causing the sections 1 and 2 and lugs 10 and 11 to weld together forming what may be termed a homogeneous joint.

When the insulation is cut away from the conductor the cut is sufficient so that the sections 1 and 2 will abut against the remaining insulation and set up an unusually neat joint.

Referring to Figs. 4 and 5 of the drawings which illustrate the sections of a three-way or T-joint, 13 denotes one section and 14 the other. Each of said sections consists of arms 15, 16 and 17 and each of said arms has a groove 18 and these latter intersect with each other at the inner ends. One of the arms of the section 13 has a laterally extending bendable lug 19 and one of the arms of the section 14 has a laterally extending bendable lug 20. These lugs 19 and 20 perform the same function as the lugs 10 and 11. The arms 15, 16 and 17 merge into each other at their inner ends and the arm 17 is disposed centrally with respect to the arms 15 and 16, these latter extending in the same plane.

40 Referring to Figs. 6 and 7 of the drawings which illustrate the sections of a two-way or L-joint, 21 denotes one of the sections and 22 the other of the sections and each of said sections consists of arms 23 and 24 which are 45 disposed at right angles with respect to each other and each of said arms has a groove 25 and the said grooves 25 merge into each other at their inner ends.

One of the arms of the section 21 has a laterally extending lug 25' and one of the arms of the section 22 has a laterally extending lug 26. The lugs 25' and 26 are disposed in opposite direction with respect to each other and perform the same function 55 as the lugs 10 and 11.

Referring to Fig. 8 of the drawing in which is illustrated the sections of a one-way or straight joint, 27 denotes one of the sections and 28 the other of the sections and 60 each of said sections is formed with a longitudinally extending groove 29. The section 27 has a laterally extending bendable lug 30 and the section 28 a laterally extending bendable lug 31. The lugs 30 and 31 are disposed 65 in opposite direction with respect to each

other and perform the same function as the lugs 10 and 11.

In Fig. 8 the ends of a pair of electrical conductors, with the insulation removed, are mounted in the groove 29 of the section 27. 70 The said conductors are indicated at 32 and 33.

Referring to Fig. 9 of the drawing, which illustrates the sections of a two-way or V-joint, 34 denotes one section and 35 the other and each of said sections is formed with two arms 36, 37, provided with a groove 38. The grooves 38 intersect each other at their inner ends. The section 34 has a laterally extending bendable lug 39 and the section 35 has a 80 laterally extending bendable lug 40. The lugs 39 and 40 perform the same function as the lugs 10 and 11.

The sections of the T-joint, L-joint, straight joint and V-joint are constructed of the same material as the sections 1 and 2 of the four-way or cross joint. The arms of the sections of the T-joint, L-joint, and V-joint are semi-cylindrical in cross section and the free end thereof reduced. The sections of the one-way or straight joint are semi-cylindrical in cross section and each of the ends of each of said sections is reduced.

The manner of using the sections of the joint shown in Figs. 4 to 9 is the same 95 method as that referred to in connection with the joints illustrated in Figs. 1 to 3.

What we claim is:—

1. A joint for electrical conductors comprising a pair of sections formed of weldable material and corresponding in contour to the shape of the joint to be formed, each of said sections having a weldable and bendable lug for connecting the sections to the conductors to be joined prior to the welding of said sections together. 100

2. A joint for electrical conductors comprising a pair of sections formed of weldable material and corresponding in contour to the shape of the joint to be formed, each 110 of said sections having a weldable and bendable lug for connecting the sections to the conductors to be joined prior to the welding of said sections together, each of said sections provided with grooves to receive 115 the ends of the conductors when freed from insulation.

3. A joint for electrical conductors comprising a pair of sections formed of weldable material and corresponding in contour 120 to the shape of the joint to be formed, each of said sections having a weldable and bendable lug for connecting the sections to the conductors to be joined prior to the welding of said sections together, each of said sections provided with grooves to receive 125 the ends of the conductors when freed from insulation, each of said lugs being disposed laterally with respect to that section with which it associates.

4. A joint for electrical conductors comprising a pair of sections formed of weldable material and corresponding in contour to the shape of the joint to be formed, each 5 of said sections having a weldable and bendable lug for connecting the sections to the conductors to be joined prior to the welding of said sections together, the lug of one section being disposed in opposite direction 10 with respect to the lug of the other section.

5. A joint for electrical conductors comprising a pair of sections formed of weldable material and corresponding in contour to the shape of the joint to be formed, each 15 of said sections having a weldable and bendable lug for connecting the sections to the conductors to be joined prior to the welding of said sections together, each of said sections provided with grooves to receive the 20 ends of the conductors when freed from insulation, the lug of one section being disposed in opposite direction with respect to the lug of the other section.

6. A joint for electrical conductors comprising a pair of sections formed of weldable material and corresponding in contour to the shape of the joint to be formed, each 25 of said sections having a weldable and bendable lug for connecting the sections to

the conductors to be joined prior to the welding of said sections together, each of said lugs arranged in proximity to one end of its respective section and the lug of one section extending in an opposite direction with respect to the lug of the other section. 30

7. A joint for electrical conductors comprising a pair of sections formed of weldable material and corresponding in contour to the shape of the joint to be formed, each 35 of said sections having a weldable and bendable lug for connecting the sections of the conductors to be joined prior to the welding of said sections together, each of said sections provided with grooves to receive the 40 ends of the conductors when freed from insulation, each of said lugs arranged in proximity to one end of its respective section and the lug of one section extending in an opposite direction with respect to the lug of 45 the other section.

In testimony whereof we affix our signatures in the presence of two witnesses.

CHARLES B. SCHOENMAN,
RALPH M. HOUCK.
